UNITED STATES PATENT OFFICE.

MARGARET R. MACE, OF PHILADELPHIA, PENNSYLVANIA.

ENVELOP-TAG.

1,139,553.

Specification of Letters Patent. Patented May 18, 1915.

Application filed July 7, 1914. Serial No. 849,483.

To all whom it may concern:

Be it known that I, MARGARET R. MACE, a citizen of the United States, residing at Philadelphia, in the county of Philadelphia and State of Pennsylvania, have invented 5 new and useful Improvements in Envelop-Tags, of which the following is a specification.

This invention relates to an envelop tag 10 adapted for use in fastening an envelop containing a bill, invoice, letter sheet or other matter to a parcel or package intended for transmission through the mail under parcel post regulations, the primary object of the 15 invention being to provide a tag which may be applied to an ordinary form of envelop and fastened to the parcel in a secure manner.

A further object of the invention is to 20 provide a tag of the character described which may be firmly secured to the envelop and may serve as a vehicle for a return card or address.

The invention consists of the features of 25 construction, combination and arrangement of parts herein fully described and claimed, reference being had to the accompanying drawing in which:—

Figure 1 is a face view of an envelop embodying the invention. Fig. 2 is a rear view of the same. Fig. 3 is a view of the tag detached.

Referring to the drawing, 1 designates an envelop of ordinary construction provided 35 with a top sealing flap 2, and 3 and 4 designate respectively the front and rear walls of the envelop body.

The tag 5 comprises an oblong rectangular strip of tough paper or other suitable 40 material provided along one of its longitudinal edges with a central tab 6 and end tabs 7 beyond said central tab, one of the faces of the tag body and the corresponding faces of the tab 7 being provided with a 45 gummed coating 8, while the central tab 6 is provided with a pair of eyeleted openings 9. Passing through these eyeleted openings

9 is the loop portion of a fastening cord 10, which is knotted at 11 to hold the looped portion of the cord from displacement, the 50 ends 12 of the cord being free for attaching the tag to a parcel post package. The other side or face of the body of the tag may be provided with a suitable form 13 to receive the name and address of the transmitter, or 55 any other suitable return card or matter.

In the use of the device, the bill, invoice or other matter to be forwarded with the parcel is placed within the envelop 1 to which the tag is applied, and the flap 2 then 60 sealed and the envelop attached by means of the cord to the parcel. In applying the tag to the envelop, the gummed faces 8 of the tag body and the flaps 7 are moistened, the tag body then secured transversely to the 65 face of the envelop at one end, and the tabs 7 then turned backwardly over the end edge 14 of the envelop and secured to the rear face of the envelop, the tab 6 projecting outwardly from the envelop, as shown in Figs. 70 1 and 2. The tag will thus be securely fastened to the envelop so that it can not become displaced.

I claim:—

An envelop tag comprising an oblong rectangular body portion gummed upon one face thereof, tabs at the ends of one of the longitudinal edges of said body portion and also having gummed faces on their side adjacent the gummed face of the body portion, said end tabs being foldable in a direction toward said gummed face of the body portion, and a center tab disposed upon the aforesaid longitudinal edge of the body portion between said gummed tabs and having 80 ungummed faces and provided with spaced eyelets for the passage of a fastening cord. 85

In testimony whereof I affix my signature in presence of two witnesses.

MARGARET R. MACE.
